UNITED STATES PATENT OFFICE.

WALTER F. SMITH, OF PHILADELPHIA, PENNSYLVANIA.

HYDRAULIC SEPARATOR.

941,663.

Specification of Letters Patent. Patented Nov. 30, 1909.

Application filed March 14, 1905. Serial No. 250,007.

To all whom it may concern:

Be it known that I, WALTER F. SMITH, a citizen of the United States, residing at Philadelphia, in the county of Philadelphia and State of Pennsylvania, have invented 5 certain new and useful Improvements in Hydraulic Separators, of which the following is a specification.

Objects of the present invention are to 10 prevent worthless material of high specific gravity, such as magnetic sand and the like, from lodging in a comparatively solid mass and occupying the spaces between the riffles where it would prevent the contained values 15 from finding a place for lodgment; to provide an apparatus which may be subjected to the operation known as "cleaning up" without suspending the performance of its ordinary functions; to provide portable apparatus 20 adapted to improve the operation and capable of application in various localities; and to facilitate the performance of the "cleaning up" operation.

To these and other ends hereinafter set 25 forth the invention comprises the improvements to be presently described and finally claimed.

The nature, characteristic features and scope of the invention will be more fully 30 understood from the following description taken in connection with the accompanying drawings forming part hereof and in which—

Figure 1, is a top or plan view of apparatus embodying features of the invention. Fig. 2, is a view partly in section and partly in elevation of the same. Fig. 3, is a view principally in section illustrating a modification of the invention. Fig. 4, is a sectional view illustrating a portion of the apparatus shown in Figs. 1 and 2, and Figs. 5 and 6, are perspective views illustrating details of one type of construction of movable riffle and agitator.

In the drawings 1, may be designated as 45 the head of sluice box or boxes provided with a suitable hopper 6, a rotary screen 3, and a water supply 4. The material to be treated is moved from the bank or deposit 50 by means of the elevator 2, and delivered into the hopper 6, from which it passes into the revolving screen 3, the coarse material escaping from the end opening of the revolving screen and the fine material, includ-

ing the values and considerable water, es- 55 caping through the perforations in the revolving screen into the head of the sluice box.

This description is of one type of apparatus which, of course, may be replaced by 60 a variety of types of apparatus designed to operate so as to deliver the comparatively fine material which contains the value to be recovered to the systems of agitators and movable riffles, to be presently described. 65

7, is a reservoir which receives the fine material and it is arranged so as to communicate with and be common to the sluice boxes or flumes, of which two, 8 and 9, are shown, although the number may be increased or diminished. 70

In each flume or slice-box there is a system of movable riffles and agitators. This element is shown to consist of endless belts or sprocket chains 10 and their appropriate 75 wheels 11, 12 and 13. These belts or sprocket chains are provided with agitators and movable riffles of suitable construction and adapted to be moved in the direction of the head of the sluice boxes. Examples of riffles 80 and agitators are shown in Figs. 5 and 6, in which *a* is the agitator part and *b*, the riffle part, but the parts are capable of various embodiments. As shown they are suspended from the belts 10 and provided with lugs 85 or stops in such a way that they are rigid when in operative position and turn down onto the belts when in inoperative position. The wheels 11, 12 and 13 may be mounted upon axles permanently connected with the 90 flume or sluice box as shown in Fig. 3, or they may be arranged upon a frame 16, as shown in Fig. 2, consisting of two arms and which frame can be detachably connected with the sluice-boxes so that it can be moved 95 from one to another. If desired, the frame may be pivoted to the sluice-box as at 17, so that it can be turned up out of the sluice-box in order to facilitate the operation of "cleaning-up". 100

Each sluice-box is provided at its discharge end with a gate 18 which permits of adjustment of the depth of material and water in the sluice-box. There is a gate 19 at the head end of each sluice-box and the 105 gate 19 that appertains to any sluice-box may be closed while it is being cleaned up, without interfering with the normal opera-

tion of the other sluice-boxes, whose gates 19 are open.

20, are gates which facilitate the removal of the material which is to be saved during 5 the "cleaning up" operation.

21, 22, 23 and 24 indicate belts or sprocket chains and their connections, which receive power as from the belt or sprocket chain 25 and transmit it to the various movable 10 parts which have been described.

Normally gate 19 is open and gate 18 properly adjusted, and water and material are flowing. The riffles and agitators are moving in the direction of the source of supply 15 and they serve to move the contained values toward the head of the box, keeping the material meanwhile agitated, so that suspended matter passes out of the box over the gate 18 and retaining in the box at or 20 near its head the heavy concentrates containing the values; while at the same time the movement of the riffles and agitators prevents undesirable lodgment of heavy material. In cleaning up the sluice-box the gate 25 19 is closed and the moving riffles and agitators draw the concentrates toward the gate

20 through which they pass and are collected.

It will be obvious to those skilled in the art to which the invention relates that modifications may be made in details without departing from the spirit thereof, hence the invention is not limited further than the prior state of the art may require, but 30

Having thus described the nature and objects of my invention what I claim as new and desire to secure by Letters Patent is— 35

In a hydraulic separator, the combination of a flume or sluice box and a series of movable riffles and agitators of which each extends entirely across the width of the box and comprises a solid lower part which operates as a riffle and a grate-like upper part which acts as an agitator, substantially as 40 described.

In testimony whereof I have hereunto signed my name.

WALTER F. SMITH.
